UNITED STATES PATENT OFFICE.

GEORGE F. ATWOOD, OF NEW YORK, N. Y., ASSIGNOR TO WESTERN ELECTRIC COMPANY, OF CHICAGO, ILLINOIS, A CORPORATION OF ILLINOIS.

WINDING-MACHINE.

No. 841,805.

Specification of Letters Patent.

Patented Jan. 15, 1907.

Application filed April 27, 1904. Renewed April 27, 1908. Serial No. 814,017.

To all whom it may concern:

Be it known that I, GEORGE F. ATWOOD, a citizen of the United States, residing at New York, in the county of New York and State of New York, have invented a certain new and useful Improvement in Winding-Machines, of which the following is a full, clear, concise, and exact description.

My invention relates to a winding-machine, and has for its object to provide an improved mechanism for winding wire upon closed cores.

The machine is particularly designed for winding "loading-coils" for telephone-circuits. Such coils consist of a ring-shaped core of laminated iron having two wire helices wound upon semicircular segments thereof.

My principal object has been to produce a machine which will apply the wire radially to coils of this character where the coils are small and have a restricted opening in the center.

I will describe my invention by reference, to the accompanying drawings, which illustrate a winding-machine embodying my several improvements, and the parts or combination which I consider novel will be pointed out in the appended claims.

Figure 1 is a view of said winding-machine in elevation, the ring-core upon which the wire is to be wound being shown in section.

Fig. 2 is a plan view of the machine. Fig. 3 is a vertical sectional elevation. Figs. 4 and

5 are detail views of a drag mechanism for the rotating spool. Fig. 6 is a detail view showing how a segment of the winding-ring may be removed to permit the ring-core to be interlinked therewith. Fig. 7 is a detail

view of the removable segment of the spool.

Fig. 8 is a detail view of a bridge-piece which is fitted over the winding-ring to support and guide the wire from the spool to the sheave on the winding-ring. Fig. 9 is a detail view

of the holder for the ring-coil. Fig. 10 is a detail view in elevation, partially in section, showing the manner in which the wire is fed from the spool over the sheave or guide to the core; and Fig. 11 is a detail end elevation, partially in section, of the parts shown in Fig. 10.

The same letters of reference are used to designate the same parts wherever they are shown.

The principal operating parts of the machine are the spool-ring *a* and winding-ring *b*, which are mounted side by side so as to rotate independently of each other, both of said rings being provided with removable segments, so that the closed core may be interlinked therewith, and the winding-ring carrying a winding sheave or guide substantially in the central plane between the two rings. The wire to be wound upon the core is led from the spool over the winding-sheave and thence to the core. The winding-ring *b* is adapted to be driven to carry the winding-sheave around and through the core, and in its rotation the wire is pulled off the spool and wrapped around the core.

In the machine shown the rings *a* *b* are supported upon two independent sets of wheels *a'* *b'*, respectively, and the wheels *b'* are arranged to be driven by sprocket-and-chain mechanism, as shown, so that as said wheels are rotated the winding-ring *b* is frictionally driven. The wheels are preferably grooved to fit corresponding inner beveled edges of the rings. The set of wheels *a'* is supported upon a suitable framework *a''*, while the set of wheels *b'* is supported upon a similar framework *b''* on the other side, the two supports being independent, so that the space in the plane between the two rings is left unobstructed to permit the passage of the wire therethrough as it is being wound. A drag is provided for the spool-ring, as shown in detail in Figs. 4 and 5. This drag may be simply a block of fiber *c*, mounted to slide in guideways *c'* upon the framework of the machine, said drag being pressed against the inner rim of the spool-ring *a* by means of a spring *d*, acting through a lever *d'*, as shown. One end of the spring may be hooked upon the lever which engages the sliding drag, while the other end may be fastened to an adjustable anchor *d''*. The spool-ring *a* is provided with a removable segment or gate *a³*, so that when said gate is removed the core *e* to be wound may be interlinked with said ring *a*. Similarly the winding-ring *b* has a segmental opening for the same purpose, the two ends of said guide-ring being normally held together by the removable turnbuckle *b³*. Said turnbuckle forms, in effect, a removable segment of said winding-ring.

When the core is to be inserted, the turnbuckle *b³* and the gate *a³* are removed, and

after the core is in position they are replaced and the turnbuckle tightened to contract the winding-ring b and bring the same into firm engagement with the friction driving-wheels $b' b'$, upon which it is supported. All the wire that is to be wound upon a given segment of the core must be first wound or spooled up upon the spool-ring a after the core has been interlinked therewith. Then the other end of the wire on the spool is led over a guiding sheave or pulley f , carried by the winding-ring to the core and fastened to the latter. Upon the rotation of the winding-ring b the winding-sheave f is carried through and around the core, so that the wire is pulled off the spool and wrapped around the core.

The winding-sheave is preferably mounted in the side of the winding-ring next the spool-ring, so that said sheave is substantially in the central plane between the two rings. A removable bridge g in the form of a segmental plate is attached to the periphery of the winding-ring and extends rearwardly for a short distance, spanning laterally the gap or space between the two rings. Said bridge-piece is preferably provided with guides or eyelets through which the wire is passed from the spool over said bridge on its way to the winding-sheave.

Preferably only the set of wheels $b' b'$ is positively driven, the wheels $a' a'$ being simply supports upon which the spool-ring may turn. In order to drive the spool-ring while the wire is being spooled up on the same, however, the two rings may be coupled to rotate together by means of a pin h , passing through them.

In the operation of the machine the segment a^3 and the turnbuckle b^3 are first removed and leave an opening through which the closed core e may be interlinked with the rings. The segment a^3 and turnbuckle b^3 are then replaced and locked in position and the two rings coupled together by means of the pin h . The machine is now ready to spool up, and this operation is shown in Fig. 2, the driving mechanism being started to rotate the rings $a b$ in the direction opposite to that in which they will turn when the wire is being unwound from the spool to the core. In spooling up the end of the wire may be simply fastened to the spool in any convenient way, the spool set to rotating, and the wire guided onto the same by the hand of the operator. During the spooling operation the drag may be taken off the spool by manipulating an adjusting-screw d^3 , acting upon a lever d' . When a sufficient quantity of wire is wound upon the spool, the bridge-piece or peripheral plate g is attached to the winding-ring, said plate extending rearwardly a short distance from the guiding-sheave. The other end of the wire is then passed through eyelets on the bridge-plate g , then passed over the

winding-sheave f , and from thence led to the core, passing through the unobstructed space between the two mountings of the rings $a b$. The end of the wire being fastened to the core, the driving mechanism is now started to rotate the winding-ring in the direction shown by the arrows in Figs. 1 and 10. It will be seen that as the ring rotates the guiding-sheave will be carried around and through the core and the wire will be wrapped around said core.

The core is held horizontally in a standard k , which is pivoted at k' to the bed-plate of the machine in such a way that the core may be rotated about a vertical axis coinciding with the axis of the core while the winding-machine is in operation to guide the wire which is being applied to said core back and forth through a semicircumference. The standard k may be rotated by means of a gear-train actuated by a ratchet-pawl m , carried upon an oscillating hand-lever l . The lever l is pivoted to be oscillated to and fro between fixed posts $o o$, and in its oscillation the ratchet-pawl m will advance the gear-train and rotate the core. When one half of the core has been wound, it may be taken out of the holding-clamps k^2 and turned around, whereupon the other half may be wound in the same manner.

Owing to the quantity of wire the spool has to carry to wind an ordinary loading-coil, room can only be obtained by making the spool of a large diameter. This necessitates a construction in which the body of the ring or coil being wound is quite eccentric to the winding-ring and spool. With a spool and winding-ring of large diameter, however, the wire is pulled off the spool during one half of a revolution, while the guide-sheave is moving away from the coil at a rate much faster than during the other half of the revolution, while the guiding-sheave is moving toward the coil. This tends to the formation of slack wire, and the braking mechanism or drag is applied to the spool to prevent the spool from rotating any faster than is required by the amount of wire to be pulled off by the movement of the guide-sheave through a given arc.

A special advantage results from mounting the guide-sheave substantially in the central plane between the two rings, for the reason that the wire may be wound radially upon the core without having any great amount of space in the restricted opening of the coil taken up by the rings of the winding-machine. In other words, a coil may be wound in which the inner diameter of the completed coil will be but slightly greater than the combined width of the spool-ring and guide-ring. As shown, the cross-sectional area of the winding-ring and spool-ring together is reduced to a minimum by rounding the sides thereof. The inside of the spool-ring is also

hollowed out, as shown, to conform to the curved outside, so that the maximum quantity of wire can be held therein without increasing the space which the ring will take up 5 in the inside of the coil being wound.

I claim—

1. In a machine for winding closed cores, the combination with a spool-ring and a winding-ring having removable segments 10 whereby they may be interlinked with a core to be wound, said two rings being mounted side by side to rotate independently, driving mechanism for the winding-ring, a frictional drag for the spool-ring, and a guide-sheave 15 carried by said winding-ring over which the wire to be wound is led from the spool to the core, whereby in the rotation of the winding-ring the wire is wound upon the core, the spool being rotated by the pull of the wire to 20 feed the same.

2. In a machine for winding closed cores, the combination with a spool-ring and a winding-ring adapted to be interlinked with the core, said two rings being eccentric to the 25 body of the core, and mounted to rotate independently, a friction-drag acting upon the spool, and friction driving-wheels engaging the inside of the winding-ring to drive the same, said winding-ring carrying a guide-sheave over which the wire is carried from 30 the spool to the core.

3. In a machine for winding closed cores, the combination with a spool-ring and winding-ring of the same diameter mounted together side by side to have the same central axis, segments of said rings being removable to permit a closed core to be interlinked therewith, a set of idler-wheels engaging the inner edge of the spool-ring, driven wheels 35 engaging the inner edge of the winding-ring, the central space between the two sets of wheels in the plane between said rings being unobstructed, and a guide-sheave mounted in the winding-ring, the wire being led from said 40 spool around said guide-sheave and onto the core, passing substantially in the central plane between the two rings.

4. In a machine for winding closed cores, the combination with a spool-ring and a 50 winding-ring mounted side by side and having removable segments to permit the core to be interlinked therewith, said rings being rotatably mounted independent of each other, means for driving the winding-ring, the rotation of the spool-ring being retarded by a drag, a guide-sheave rotatably mounted upon the winding-ring substantially in the central plane between the two rings, and a bridge-piece removably mounted upon the periphery of the winding-ring and extending rearwardly from the guide-sheave to permit the wire to be led from the spool over said bridge-piece to the guide-sheave and thence to the core.

5. In a machine for winding closed cores,

the combination with a spool-ring and a guide-ring adapted to be interlinked with the core, independent supports for said rings, whereby the same may rotate independently about the same central axis, a clear space being 70 left in the plane between the two rings, and a guide carried by the winding-ring substantially in said plane between the two rings, the wire to be wound being led from the spool through said guide and onto the core, 75 whereby in the rotation of the winding-ring the wire is pulled off the spool and wound upon the core, the spool being rotated by the pull of the wire to feed the same.

6. In a machine for winding closed cores, 80 the combination with a spool-ring and a winding-ring, removable segments for said rings whereby they may be interlinked with a core to be wound, said rings being mounted side by side to rotate independently, the 85 outer surface of each ring being rounded to conform to the space inside of the core, and mechanism operated in the movement of the winding-ring adapted to lead the wire from said spool-ring and wind the same through 90 and around the core.

7. In a machine for winding closed cores, the combination with a spool-ring and a winding-ring adapted to be interlinked with a core to be wound, said rings being rotatably mounted side by side with their outer 95 surfaces rounded, the spool-ring being hollowed out to conform to the curved outside thereof, and mechanism adapted to operate said rings to wind the wire upon the core; 100 whereby the maximum amount of wire may be held within the spool-ring, and a coil wound to have a minimum inner diameter when completed.

8. In a machine for winding annular cores, 105 the combination with a rotatable spool-ring adapted to be interlinked with the core, of a rotating guide adapted to lead the wire from said spool-ring and wind the same through 110 and around said core, said guide and spool-ring being mounted side by side to rotate independently, mechanism for rotating said guide, a support for said core pivoted to rotate upon an axis substantially coincident with the axis of the core held thereby, and 115 mechanism adapted to rotate said support upon its axis, whereby the wire may be rapidly wound upon said core in even and regular convolutions, substantially as set forth.

9. In a machine for winding closed cores, 120 the combination with a spool-ring and a winding-ring adapted to be interlinked with a core to be wound, said rings being mounted side by side to rotate independently, a guide carried by the winding-ring over which the 125 wire to be wound is led from the spool-ring to the core, the spool-ring being rotated by the pull of the wire as the winding-ring is moved to feed the same, and driving mechanism for said winding-ring; whereby as the winding- 130

ring is rotated the guide is carried around and through the core and the wire wound thereon.

10. In a machine for winding closed cores, the combination with a spool-ring adapted to be interlinked with a closed core, of a rotating guide adapted to lead the wire from the spool-ring and wind the same through and around the core, said guide and spool rings being mounted side by side to rotate independently, and means for operating said guide.

11. In a machine for winding closed cores, the combination with a spool-ring and a guide-ring having removable segments whereby they may be interlinked with a core to be wound, said rings being mounted side by side to rotate independently, the guide-ring being adapted when operated to lead the wire from said spool-ring and wind the same upon said core, and means adapted to rotate said guide-ring, the spool-ring being rotated by the pull of the wire to feed the same, as the guide-ring is turned.

12. In a machine for winding annular cores, the combination with a rotatable spool-ring adapted to be interlinked with the core, of a rotating guide adapted to draw the wire from said spool-ring and thread the same through and around the core, mechanism for rotating said guide, a standard carrying clamps adapted to hold the core to be wound, said standard being mounted to rotate upon a vertical axis substantially coincident with the axis of the annular core held thereby, a gear adapted to rotate said standard, and an oscillating lever carrying a pawl adapted to actuate said gear, whereby the wire may be radially applied to the core being wound.

13. In a machine for winding closed cores, the combination with a spool-ring and a winding-ring adapted to be interlinked with a closed core, said rings being mounted side by side to rotate independently, driving mechanism for said winding-ring, a guide carried by the winding-ring over which the wire to be wound is led from the spool-ring to the core, and means actuated in the movement of the winding-ring for rotating said spool-ring to feed the wire to be wound.

14. In a machine for winding closed cores, the combination with a spool-ring and a winding-ring adapted to be interlinked with a closed core, said rings being mounted side by side to rotate independently of each other, driving mechanism for said winding-ring, a guide carried by the winding-ring over which the wire to be wound is led from the spool-ring to the core, said guide being disposed in substantially the central plane between the two rings, and means actuated in the movement of the winding-ring adapted to rotate said spool-ring to feed the wire to be wound.

15. In a machine for winding closed cores, the combination with a spool-ring and a winding-ring adapted to be interlinked with

a closed core, said rings being mounted to rotate independently, driving mechanism for said winding-ring, a guide-sheave carried by said winding-ring over which the wire to be wound is led from the spool to the core, the spool-ring being rotated as the winding-ring is moved by the pull of the wire to feed the same, a support for said core, and mechanism adapted to rotate said support, whereby the wire applied to said core is guided back and forth through a semicircumference.

16. In a machine for winding closed cores, the combination with a spool-ring and a winding-ring, removable segments whereby said rings may be interlinked with a closed core, said rings being mounted side by side to rotate independently, driving mechanism for said winding-ring, a guide-sheave carried by said winding-ring over which the wire to be wound is led from the spool-ring to the core, the spool-ring being rotated by the pull of the wire as the winding-ring is moved to feed the same, a standard adapted to support the core being wound, a gear-train adapted to rotate said standard back and forth through a semicircumference, and a manually-operated mechanism for operating said gear-train; whereby the wire is evenly applied to the segment of the core being wound.

17. In a machine for winding closed cores, the combination with a spool-ring and a winding-ring adapted to be interlinked with a closed core, said rings being mounted side by side to rotate independently, driving mechanism for said winding-ring, mechanism actuated in the rotation of the winding-ring adapted to guide the wire from the spool-ring to the core, the spool-ring being rotated by the pull of the wire as the winding-ring is moved to feed the same, a frictional drag acting upon said spool-ring, and mechanism adapted to adjust the same to maintain a constant tension on the wire being wound.

18. In a machine for winding closed cores, the combination with a spool-ring adapted to be interlinked with a core in eccentric relation thereto, of means for leading the wire from the spool-ring to the core, and means for taking up slack wire.

19. In a machine for winding closed cores, the combination with a spool-ring adapted to be interlinked with a core of a diameter less than said ring, said core being eccentrically mounted with respect to said ring, a movable guide for leading the wire from the spool-ring to the core, and means for taking up the slack wire.

20. In a machine for winding closed cores, the combination with a spool-ring adapted to be interlinked with a core, said ring being of larger diameter than the core, said ring being disposed eccentrically with respect to the portion of the core embraced thereby, means for pulling the wire from the spool and winding it upon the core, and means for taking up

slack wire due to the eccentric relation of the spool and core.

21. In a machine for winding closed cores, the combination with a spool-ring and winding-ring adapted to be interlinked with a core to be wound, said winding-ring being adapted to lead the wire from the spool-ring and wind it upon said core, said rings being eccentrically disposed with respect to said core, and means for taking up slack wire.

22. In a machine for winding closed cores, the combination with a core to be wound, of a spool-ring and winding-ring of larger diameter than said core adapted to be interlinked therewith, said winding-ring being adapted to lead the wire from the spool-ring to wind it upon said core, said rings being eccentrically disposed with respect to said core, and braking mechanism for the spool-ring, adapted to take up slack wire.

23. A machine for winding closed cores comprising a spool-ring and winding-ring

mounted side by side to rotate independently, said rings being adapted to be interlinked with a core, the winding-ring in its rotation pulling wire off said spool-ring and winding the same upon the core.

24. A machine for winding closed cores comprising a spool-ring and winding-ring mounted side by side to rotate independently, said rings being adapted to be interlinked with a core, the winding-ring in its rotation pulling wire off said spool-ring and winding the same upon the core, said rings being eccentrically disposed with respect to said core.

In witness whereof I hereunto subscribe my name this 16th day of February, A. D. 1904.

GEORGE F. ATWOOD.
